UNITED STATES PATENT OFFICE.

WALTER A. CHURCH, OF BINGHAMTON, NEW YORK, ASSIGNOR TO THE
BRISTOL BRASS & CLOCK COMPANY, OF BRISTOL, CONNECTICUT, A
CORPORATION OF CONNECTICUT.

COMBINED SOCKET AND ROSETTE.

No. 806,107.

Specification of Letters Patent.

Patented Dec. 5, 1905.

Application filed December 6, 1902. Serial No. 134,133.

To all whom it may concern:

Be it known that I, WALTER A. CHURCH, a citizen of the United States, and a resident of Binghamton, in the county of Broome and 5 State of New York, have invented certain new and useful Improvements in a Combined Socket and Rosette, of which the following is a specification.

My invention relates to that class of supports for an electric light to which the lamp 10 may be rigidly secured or supported, as by means of wires; and the object of my invention is to provide a device of this class that shall be extremely durable and efficient and 15 one consisting of a small number of parts which may be economically constructed. A form of structure in the use of which these objects may be attained is illustrated in the accompanying drawings, in which—

20 Figure 1 is a view in central section through a rosette embodying my invention. Fig. 2 is a bottom view of the cap. Fig. 3 is a plan view of the base. Fig. 4 is a perspective view showing the construction of the contacts. Fig. 5 is a plan view of the base, 25 showing another form of embodiment of the invention. Fig. 6 is a view in side elevation, showing means for rigidly connecting the lamp with the base. Fig. 7 is a perspective 30 view showing the contacts embodied in the structure of Figs. 5 and 6.

In the accompanying drawings the numeral 1 denotes the base of the structure, having a 35 chamber 2 and recesses 3 located in the bottom of the chamber. Openings 4 are formed through the bottom of the base, and grooves 5 extend from each of these openings to the recesses in the bottom of the base provided for the reception of contact members. Each 40 of these contacts is constructed from a single piece of metal first cut to proper shape to produce the final form, which is obtained by bending the parts to the form shown in the lower device of Fig. 4. Each contact consists of a foot 6, which is engaged by a screw 7, projecting through the bottom of the base to secure the conductor in place. A clamp-screw 8 is employed for securing the 45 end of the line-wire. A branch 9 extends 50 upward from the foot, and its upper portion is bent inward, forming a part 10. A branch

11 extends upward from the opposite side of the foot, its upper end also being curved inward and forming a contact 12, overlying the contact 10. It is to be noted that the contact 55 members of the base have all except their upper extremity entirely inclosed in the recesses 3, and, as hereinafter described, when the cap is in place these contacts are entirely isolated one from the other in their individual 60 chambers.

The cap 12^a has a central opening 13 for the reception of the lamp-wires. The cap is provided with central projections 14 to protect the several parts through which the electricity 65 travels. It is to be noted that the projections 14 of the cap are provided with recesses in which the contact members 15 are located, and as the projecting insulation extends beyond the contact members when the cap is in 70 place with reference to the base isolated chambers are formed, partially in the cap and partially in the base, within which the coöperating contacts of the base and cap are completely inclosed and isolated one from the 75 other. Contact members 15 are secured to the cap, as by means of screw 16, and clamp-screws 17 are employed for attaching the lamp-wires to each contact member. Each 80 of the contact members is provided with an offset portion 18, forming a contact. It will be noted that these contact members are located in recesses in the cap, the lamp-wires being led through grooves into these recesses 85 in which the conductors are located, so that there is little danger in attaching the cap to the base that parts not so intended can touch each other, and thus short-circuit the device.

In the form of device shown in Figs. 5, 6, and 7 the contact member secured to the base 90 19 is formed in two parts and projects through the wall 20 outside of the central recess in the base. The foot 21 of the contact member bears a binding-screw 22 for securing the line-wires in place. The contact is formed of a 95 single piece of metal having a branch extending upward from one side and bent inward, forming a lip 24, and a branch extends upward from the opposite side and is bent inward, forming a lip or contact 23. The attaching-screw 25, which passes upward 100 through the bottom of the base, also passes

through the bottom of the contact and through the foot 21 into the lip 24, thus securing the parts in position. A contact 26 is secured to the cap and is similar in construction to that 5 described with reference to Figs. 1, 2, 3, and 4, the engagement of the cap with the base being formed in the same manner. While the description has been confined to a single contact on the cap and on the base, it will be 10 understood that there are a plural number of such devices on each of the parts.

The cap 27 may be provided on its outer surface with a recess 28, in which a lamp-socket 29 may be located, the screws 30 in this 15 instance, which bind the two portions of the lamp-socket together, extending into the cap to unite the socket thereto and also engaging the contacts 26, if desired, for the purpose of holding the latter in place. The screws 30 20 also secure the contacts and bearing-plates 31 in position.

What I claim as my invention, and desire to secure by Letters Patent, is—

1. A base of insulating material, contacts 25 secured to the base, each including a foot, an arm extending upward from the foot and having its end bent at an angle to the main part and forming a coöperating contact, and a second arm extending upward from the same 30 base and having its bent end overlying said first-named contact part, all of the several parts formed from a single piece of material bent to shape, a cap, and contacts arranged thereon each provided with an end adapted 35 to enter between the contacts of the base and be clamped thereby.

2. A base of insulating material, contact devices mounted therein each consisting of a base, an arm projecting upward from one side 40 of the base with its end bent to form the contacting surface, an arm projecting upward from the opposite side of the same base, with its bent end overlying said contacting part, the several parts formed from a single piece 45 of material bent to shape, a cap, and contacts borne by the cap each having an end adapted to enter between the ends of the contact on the base and coöperating therewith to hold the base and cap securely together.

50 3. A base of insulating material, a contact consisting of a foot having means for attachment of a line-wire, arms extending upward from opposite sides of the foot, each having bent ends one overlying the other and parallel 55 with relation to each other, one of said arms having a part projecting into the space between the parallel overlying ends and forming a detent for a coöperating contact member, a cap, and contacts arranged upon the 60 cap and adapted to enter between the ends of the contact on the base, and be engaged and held by the said base-contacts.

4. A base, contacts secured to the base each including a foot, arms projecting upward

therefrom and with their ends bent the one 65 overlying the other, the several parts formed from a single piece of material bent to shape, a cap, contacts secured to the cap each having an end adapted to enter between the ends of the contact on the base, and means for securing the wires to said parts. 70

5. A base, contacts secured to the base each having arms extending upward from opposite sides of the base and with their ends bent inward the one overlying the other in parallel 75 relation, a cap, contacts secured to the cap each having its end adapted to enter between the bent ends of the conductors on the base, and means for securing wires to said parts.

6. A base, contact-recesses arranged on opposite sides of the center of said base, contacts located within said recesses, and having a part extending above the base-recesses, an outer rim upon the base extending above the contacts, a cap having a projection from the 85 central portion thereof extending within and meeting the base, clamps secured in recesses formed in the side of said projection, cap-contacts located in recesses formed in said central projection and with their ends only projecting beyond the projection, said contacts adapted to engage the base-contacts upon partial rotation.

7. A base having contacts, said base having a peripheral flange extending above the 95 contacts, a cap having a central projection, extending within and meeting the base, and provided with a central opening, wire-clamps located in recesses formed in the periphery of and on diametrically opposite sides of the 100 projection, grooves from the central opening through the body of the projection into said recesses, contacts located as to their body parts in recesses formed in the body of, and on diametrically opposite sides of said cap 105 projection, said contacts having their contacting ends projecting beyond the cap projection, and arranged to engage the contacts of the base, and connections between the clamps and contacts. 110

8. In combination in a rosette, a base of insulating material having depressed recesses to receive contacts whereby the contacts are isolated and insulated one from the other, contacts arranged in said depressed recesses, 115 a cap bearing coöperating contact members, the latter arranged within depressions in the cap and an integral boss projecting from the cap about and beyond the contacts and engaging the base and coöperating therewith to 120 form isolated chambers for each of the contact members when in engagement.

9. A base of insulating material having contact-recesses at its bottom, and provided with an outer rim extending above the contacts carried therein, recesses formed in the inner wall of said rim, and joining the contact-recesses at the base, base-contacts located 125

in the base-recesses, and with contacting parts projecting upward along the wall-recesses, a cap having a central boss fitting within the rim of the base, and projecting to the bottom thereof, contact-recesses formed in said boss, grooves and a central opening connecting with said recesses, and contacts having their body part located in the recesses

of the boss, and with their contacting ends projecting beyond the periphery of said boss, ¹⁰ said contacts adapted to engage the base-contacts in the wall-recesses.
